UNITED STATES PATENT OFFICE.

CHARLES LOUIS LAUREAU, OF PARIS, FRANCE.

TOOL POST OR HOLDER FOR METAL-WORKING MACHINES, SUCH AS LATHES, PLANING-MACHINES, SHAPING-MACHINES, AND THE LIKE.

1,259,531.

Specification of Letters Patent. Patented Mar. 19, 1918.

Application filed December 31, 1915. Serial No. 69,631.

To all whom it may concern:

Be it known that I, CHARLES LOUIS LAUREAU, citizen of the Republic of France, residing at 214 Rue de la Convention, Paris, in the Republic of France, have invented new and useful Improvements in Tool Posts or Holders for Metal-Working Machines, Such as Lathes, Planing-Machines, Shaping-Machines, and the like, of which the following is a specification.

This invention relates to improvements in tool post or holder for lathes, planing machines, shaping machines and like metal working machines, the object being to prevent the cutting tools thereof chattering or digging into the work during the cutting operation, and permit the cutting angle of the tool being adjusted to accord with the character of the work without the necessity of removing or grinding the tool.

The invention will be fully described hereinafter with reference to the annexed drawings in which:

Figure 1 shows a lathe equipment embodying the present invention.

Figs. 2—2^a, 3—3^a and 4—4^a illustrate three different positions of the improved equipment showing the variations of the cutting angle, Figs. 2^a, 3^a and 4^a being respectively sections of the tool taken on lines A A, B B and C C of Figs. 2, 3 and 4.

Figs. 5 and 6 show two modified forms of the equipment applied respectively to a planing machine and to a shaping machine.

Figs. 7 and 8 are a side elevation and end view of the improved equipment for lathes, planing machines and the like which prevents chattering and engagement of the tool in the piece to be worked, the arrangement being such that the cutting angle of the tool cannot be modified without grinding the same.

The present invention consists essentially in combining with the tool holder carriage provided with slides, enabling its movement during the operation, a tool connected to said carriage so as to have its cutting edge turned toward the opposite side of the carriage, means for giving to the tool an inclined position with relation to the plan of the slides of the carriage, the cutting end of the tool being on the side of the apex of the acute angle formed by the line of the tool with the plan of the carriage slides, and

means for removably fixing the tool to the carriage.

Besides the above arrangement will be such that in most cases, the means which allows of giving the tool an inclined position with relation to the plan of the carriage slides, will consist in a metallic block resting upon the carriage by one face parallel with the plan of the slides and having its opposite face, against which bears the tool, inclined with relation to the plan of the slides, the connection between the tool, the inclined faced block and the carriage being such that it is possible to cause the inclined faced block to pivot about itself between the tool and the carriage, so as to vary the cutting angle of the tool, without removing said tool from its holder and without modifying the angle of its cutting edge.

Referring to Fig. 1 which illustrates a form of the improved equipment for lathes, the equipment comprises an inclined faced block 1 which rests upon the carriage 2 of conventional form.

The tool *a* is fixed upon the block 1 parallel with the inclined face thereof by means of a slotted support 2.

The assemblage (1, 2) is fixed to the carriage in such a manner that by a very simple manipulation the inclined faced block 1 may be pivoted between the support 2 of the tool and the carriage; this result is obtained by means of a single bolt the shank 3 of which passes through parts 1 and 2 perpendicularly to the inclined face of the block 1 and the head 4 of which is capable of oscillating about its geometrical axis in the T shaped slot of the carriage in which it is mounted. To afford the desired pivotal movement to the bolt, its head 4 is made of spherical formation and is engaged in a bushing 5 which fits the slot and is provided with a spherical cavity having a conical opening or mouth adapted to allow of the free movement of the head and shank of the bolt. The shank 3 of the bolt passes through an elongated hole 6 in the block 1. It will be readily seen that if the tool *a* is arranged in the support 2, so that its cutting edge is turned toward the top, and if the tool is brought into contact with the work so that the contact point is at the level of the axis thereof, as in the position illustrated in Fig. 1, and the work is rotated in

the direction of the arrow y , which is the normal direction of operation of the lathe, the tool will work without chattering and without digging into the work as in the 5 event of abnormal resistance being offered by the tool it will tend to move away from the work and will be consequently disengaged therefrom.

To vary the cutting angle of the tool, so 10 as to adapt it to the hardness of the work, it is only necessary to unfasten the fixing nut 7 of the bolt, and to pivot the inclined faced block 1 between the support 2 and the carriage b .

15 Referring to Figs. 2—2^a, 3—3^a and 4—4^a, it will be seen that for the normal position of the block 1 (Fig. 2), the cutting angle of the tool is represented by α .

If the block 1 is pivoted or turned to 20 the position shown in Fig. 3 the cutting angle becomes equal to $\delta < \alpha$ and likewise, if the block 1 is pivoted in the opposite direction, as shown in Fig. 4, the cutting angle becomes equal to $\gamma > \alpha$.

25 As soon as the block 1 has been set to give the tool the desired cutting angle, the nut 7 is tightened so as to firmly secure the parts 1 and 2 on the carriage b .

The pivotal movement of the inclined 30 block allows of the tool being inclined in certain lathe operations so that its heel is disengaged, for instance during screw cutting operations or the cutting of grooves according to circles in the work on the table.

35 Finally, the inclined block owing to the provision of elongated hole 6 therein, may be moved toward or away from the work to rapidly adjust the cutting edge to the required height.

40 Figs. 5 and 6 show the invention applied respectively to a planing machine, and a shaping machine. The means for securing the tool on the tool holder carriage above described (see Fig. 1) could be used in connection with the planing machine and shaping machine, but two other fixing means 45 have been illustrated by way of example.

In Fig. 5 which refers to a planing machine, the vertically movable tool holder carriage is designated by 8 and the inclined faced block by 9. The tool 10 is secured directly on the inclined face of the said block by means of a shackle 11 the heel 11^a of which is located in the usual T shaped 55 slot of the carriage 8. A screw 12 engaged in the nut formed in the head of the shackle presses upon the tool to assure its fastening. To adjust the cutting angle, the screw is unfastened and the block 9 is pivoted between the legs of the shackle in the proper direction.

In Fig. 6, which refers to a shaping machine, the vertically movable tool holder carriage is designated by 13, the inclined faced 60 block by 14 and the tool by 15. The latter

is secured directly on the inclined face of the block by means of a slotted member the head 16 of which is engaged in a recess of the carriage and the opposite end 17, of which receives a screw 18 adapted to secure 70 the tool in the slot 19 of the said member. To adjust the cutting angle, it is only necessary to unfasten the screw 18 and to pivot the block 14 in the proper direction about the slotted member.

75 The construction of equipment shown in Figs. 7 and 8 may be used on lathes, planing machines and the like but differs from those previously described in that it does not allow of the cutting angle being changed 80 without grinding the tool. The tool 20 is secured by fastening screws in the inclined slot 21 of the block 22 and the latter is fixed on the tool holder carriage 23 by means of a fastening shackle 24 and a bolt 25 the head 85 of which is engaged in the T shaped slot of the carriage. With this arrangement the tool holder and the carriage are also connected so as to insure the desired obliquity of the tool and the parallel movement of the slides 90 in order to avoid the tool chattering or digging into the work.

95 It will be understood that the invention can be applied to other metal working machines.

Having now described my invention, what I claim as new and desire to secure by Letters Patent is:

1. A tool post or holder for metal working machines such as lathes, planing machines, shaping machines and like machines, comprising in combination a block having an inclined face,—means for fixing said block to the tool holder carriage,—and means for connecting the tool to said block in such a 100 manner that the tool inclination intersects the plane of movement of the tool slide and the face of the tool looking toward the carriage is always kept parallel to the inclined face of the block, substantially as described 110 and for the purpose set forth.

2. A tool post or holder for metal working machines such as lathes, planing machines, shaping machines and like machines comprising in combination a block having an inclined face,—means for fixing said block to the tool holder carriage, and means for fixing the tool directly against the inclined face of the block, substantially as described and for the purpose set forth.

120 3. A tool post or holder for metal working machines such as lathes, planing machines, shaping machines and like machines comprising in combination a block having an inclined face, means for removably connecting said block to the tool holder carriage so as to enable the block to pivot about itself, and independent means for fixing the tool directly against the inclined face of the block in such a manner that the tool inclina- 130

tion intersects the plane of movement of the tool slide, substantially as described and for the purpose set forth.

4. A tool post or holder for metal working machines such as lathes, planing machines, shaping machines and like machines comprising in combination a block having an inclined face, and means for removably connecting and fastening together the tool, the said block and the carriage in such a manner as to enable the block to pivot about itself between the carriage and the tool and

to enable the tool inclination to intersect the plane of movement of the tool slide, substantially as described and for the purpose 15 set forth.

In testimony whereof I have signed my name to this specification in the presence of two subscribing witnesses.

CHARLES LOUIS LAUREAU.
